(57) **CLAIM**

The ornamental design for a water filter pitcher, as shown and described.

DESCRIPTION

FIG. 1 is a front perspective view of a water filter pitcher, showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines in the figures are for the purposes of illustrating portions of the water filter pitcher that form no part of the claimed design.

1 Claim, 8 Drawing Sheets
